UNITED STATES PATENT OFFICE.

MARTIN HOKANSON, OF DULUTH, MINNESOTA, ASSIGNOR TO MARSHALL-WELLS COMPANY, OF DULUTH, MINNESOTA, A CORPORATION OF NEW JERSEY.

TOOL HANDLE.

Application filed September 25, 1922. Serial No. 590,381.

To all whom it may concern:

Be it known that I, MARTIN HOKANSON, a citizen of the United States, resident of Duluth, county of St. Louis, State of Minnesota, have invented certain new and useful Improvements in Tool Handles, of which the following is a specification.

My invention relates to the handles of shovels, spades, scoops and the like, and the object of the invention is to eliminate the metal tube or socket usually provided for the insertion of the wooden handle therein, thereby dispensing with the joint between the end of the socket and the wooden handle which often becomes rough, to the damage of the workman's hand, and the metal socket besides being difficult to fit snugly and smoothly to the surface of the handle is unpleasant for the workman to handle in cold weather.

A further object is to provide a wooden handle which will have a smooth wood surface for the workman to grasp which will be much easier on the workman's hands than a handle that is partly of wood and partly of metal.

Other objects of the invention will appear from the following detailed description.

The invention consists generally in various constructions and combinations all as hereinafter described and pointed out in the claims.

In the accompanying drawings forming part of this specification,

Figure 1 is a plan view of a shovel embodying my invention.

Figure 2 is a side view partially broken away showing the manner of mounting the wood handle sections to the shank of the blade.

Figure 3 is a rear view showing the wood sections removed from the reinforcing shank.

Figure 4 is a sectional view on the line 4-4 of Figure 1. Figure 4^a is a sectional view on the line 4^a-4^a of Figure 1.

Figure 5 is a sectional view on the line 5-5 of Figure 1.

Figure 6 is a detail view showing the tapered form of reinforcing shank.

Figure 7 is a plan view illustrating a modified form of the reinforcing shank.

Figure 8 is a view with the wood sections omitted and showing a tapered shank.

Figure 9 illustrates a section of the reinforcing shank with an auxiliary section extending beyond the same. 55

Figure 10 is a similar view showing the auxiliary section reduced or tapered toward its outer end. 60

Figure 11 is a detail view of the auxiliary reinforcing section that is preferably secured to the shovel blade shank.

Figure 12 is a sectional view on the line 12-12 of Figure 9. 65

Figure 13 is a plan view of a shovel showing the reinforcing shank secured to the shovel blade instead of forming a part thereof.

Figure 14 is a detail sectional view showing the preferred manner of securing the shank in Figure 13 to the shovel blade. 70

Figure 15 is a sectional view on the line 15-15 of Figure 13.

Figure 16 is a view of the shank separated from the blade, showing the manner of folding the blade at one end to form the shank. 75

Figure 17 is a sectional view on the line 17-17 of Figure 16. 80

Figure 18 is a view showing the folded shank and the tapered reinforce extending therefrom.

In the drawings, 2 represents the blade of the shovel. Instead of providing the usual socket for the end of the wooden handle, I fold the metal of which the blade 2 is composed to form a substantially flat reinforce blade 3; a cross-section of this blade being in substantially the form of a flat tened U, with the side members adjacent each other and in substantially parallel relation. The usual depression 4 will be formed in the blade but the flattened shank or reinforce blade 3 will take the place of 95 the usual hollow extension or socket into which the wood handle is inserted.

The handle composed of longitudinally divided wood sections 5 is fitted on each side of the blade or shank 3, extending throughout the length of the tool handle, and these wood sections are secured in place by a suitable means, such as rivets 6 which pass through the wood sections and through the metallic reinforcing blade or shank, and rigidly secure them together. The shank may terminate in the wood handle at a point where it is subjected to a minimum strain, 100 105

but at the point near the blade where the tool handle nearly always breaks, there will be a sufficient body of metal in the reinforce or shank to brace and stiffen the handle at this point and permit the tool to be subjected to all manner of rough usage without danger of breaking.

The reinforcing blade extends the full length of the handle, but is substantially covered by the wood sections so that the workman's hands do not come in contact with the metal, always an objection in cold weather, and the joint usually formed between the metal socket and the wood handle is entirely eliminated, being a smooth continuous surface on which the workman's hand may slide without obstruction and without danger of injury, entirely to the end of the handle, or at the point where it joins the blade. The blade is preferably turned or folded as indicated at 7 in Figure 3, forming a foot-rest for convenience in forcing the tool into the ground; and the usual hand-grip 8 is provided at the other end of the handle.

The rivets passing through the handle and blade or shank, are all countersunk as indicated in Figure 5, so there is no possibility of injuring the hand of the workman as it slides on the handle.

In Figure 6, I have shown the reinforcing blade tapered or gradually decreasing in thickness from the blade to the outer end, thus reducing the amount of metal used, eliminating unnecessary weight, and only using the heavier portions of the blade at the point where it is subjected to the greatest stress. This tapered blade I will indicate by reference numeral 8'.

In Figure 7, a blade 9 is shown which terminates near the middle of the wood handle, instead of extending to the end thereof; the blade, however, being folded to form parallel side members in the manner described with reference to the previous figures. The wood sections are provided upon opposite sides of this blade extending to the end of the shovel blade in substantially the same manner as described with reference to previous figures.

In Figure 8, a tapered blade 10 is shown, rolled or reduced in thickness toward its outer end for the purpose of eliminating weight and only employing a considerable body of metal at the point where the shank is subjected to the greatest stress.

In Figure 9, a short shank 11 is folded or formed from the blade, and within this shank, a short reinforcing blade 12 is placed on edge, extending to the outer end of the handle with provision for clamping the wood sections thereto upon both sides.

Figure 10 illustrates the same idea with a taper 13 formed in the reinforcing blade, the flattened or hollowed shank terminat-

ing at substantially the same point as in an ordinary shovel.

In Figure 11, I have shown the metallic reinforce that is fitted into the folded shank of the shovel and secured thereto and to the wooden handle sections by rivets as shown and described with reference to Figure 7. An edge view of this reinforcing plate is shown in Figure 9.

In Figure 12, the folded shank of Figure 9 is shown in cross-section, within which is indicated the single unfolded reinforcing plate 12.

In Figure 13, the shank 14 is shown adapted to receive a folded reinforcing blade 15 between its walls, as in Figure 15; the wood sections being secured thereto substantially as heretofore described. This reinforcing blade 15 is preferably formed from sheet metal folded upon itself and adapted to fit into the fold of the shank making four thicknesses of the metal at this point. A flaring plate 16 is integrally formed at one end of the blade 15 and is adapted to snugly fit the surface of the depression 4 provided in the back of the shovel blade 2 and is firmly secured thereto by rivets 17, as particularly shown in Figure 14.

In Figure 15, the folded shank is shown, within which is also provided the folded reinforcing plate upon opposite sides of which the handle sections are arranged and secured.

Figure 16 shows the edge of the reinforcing blade of Figure 14 with a plate provided at the end fitting the hollow back of the shovel and secured thereto; the view being a detail of the blade of Figure 14 separated from the shovel.

In Figure 17, a detail of the plate at the end of the reinforcing blade is shown indicating the fold therein to fit the back of the shovel and showing the flanged portions which are securely riveted to the blade of the shovel.

In Figure 18, the shank 14 is shown folded to provide opposite parallel walls between which the folded reinforce plate 18 is inserted, a taper being provided in this reinforce for the purpose of reducing weight, providing a better balance for the tool, and locating the point of greatest strength in the reinforce at the point in the handle where it would be subjected to the maximum stress.

It may be said, therefore, that these different constructions embody an improved type of shovel shank and reinforce, dispensing with the well-known socket in which the wood handle is usually mounted, and providing in place thereof, a substantial shank and reinforce which will greatly strengthen the handle at the point where it is subjected to the maximum stress, will permit the formation of a smooth continuous surface on the handle on which the workman's hands may

slide, and be more substantial and durable for a tool handle construction, than anything of this nature heretofore devised.

The pressing of the shank and reinforce 5 out of the metal of which the shovel blade is composed not only will effect an economy in production but a considerable improvement in neatness of appearance and workmanship, while the taper of the shank and reinforce 10 force permits the production of a tool of better balance and one in which great strength at points of little stress will be avoided and proper safety provided at points where breakage usually occurs.

15 I claim as my invention:

1. A shovel, scoop or spade comprising a blade having a handle reinforcing extension at one end that is folded longitudinally to form opposite substantially parallel walls 20 at right angles substantially to the plane of said blade, the end of said blade adjacent said extension having foot engaging flanges formed thereon, the inner ends of the walls of said extension having curved continuations which unite with the inner ends of said flanges to brace and strengthen said blade at the point of maximum strain.

2. A shovel, scoop or spade comprising a blade having a handle reinforcing extension 25 at one end that is folded longitudinally to form opposite substantially parallel walls at right angles substantially to the plane of said blade, the end of said blade adjacent said extension having foot engaging flanges formed thereon, the inner ends of the walls of said extension having curved continu-

tions which unite with the inner ends of 40 said flanges to brace and strengthen said blade at the point of maximum strain, and a wood handle composed of longitudinally divided sections fitting the outer faces of said extension and having their inner ends seated 45 against the curved continuations of its walls and secured together through said extension.

3. A shovel, scoop or spade comprising a blade having a handle reinforcing extension at one end that is folded longitudinally to 50 form opposite substantially parallel walls at right angles substantially to the plane of said blade, a wood handle composed of longitudinally divided separable sections fitting the outer faces of said extension and having 55 their inner ends seated against curved continuations of its walls and secured together through said extension, and a reinforcing blade fitting within said extension and between said handle sections.

4. A shovel, scoop or spade, comprising a blade having a centrally arranged longitudinal extension that is folded lengthwise to form a seat for the handle, said blade having its end on both sides of said extension folded 65 to form foot engaging flanges, the walls of said extension being curved outwardly and merging into said flanges and forming therewith an integral brace and support, for said blade at its junction with said extension.

In witness whereof, I have hereunto set my hand this 20th day of September 1922.

MARTIN HOKANSON.
